UNITED STATES PATENT OFFICE.

JOSEPH INGELS, OF MILTON, INDIANA.

IMPROVEMENT IN GRAIN-DRILLS.

Specification forming part of Letters Patent No. 37,345, dated January 6, 1863.

To all whom it may concern:

Be it known that I, JOSEPH INGELS, of Milton, in the county of Wayne and State of Indiana, have invented a certain new and useful Improvement in Seeding-Machines; and I do hereby declare the following to be a full and exact description of the same, reference being had to the accompanying drawings, making part of this specification, in which—

Figure 1 is a horizontal section at $x x$, Fig. 2, of a drill illustrating my improvements and adapted for sowing both grain and grass seed. Fig. 2 is a vertical section of the same at $y y$, Fig. 1. Fig. 3 is an oblique section at $z z$, Fig. 2. Fig. 4 is a perspective view of one of the secondary or delivery hoppers, hereinafter described. Figs. 5, 6, 7, and 8 are diagrams illustrating different forms of gear-wheels employed to vary the feed, and which will be hereinafter more particularly referred to. Fig. 9 is a perspective view of the clutch-wheel and device for operating the same. Fig. 10 is a perspective view of a portion of the under side of the grass-seed hopper. Fig. 11 is a perspective view on a larger scale, illustrating the manner of attaching and adjusting the shaft upon which the movable intermediate gear-wheels run.

Similar letters of reference indicate corresponding parts in the several views.

My improvements particularly consist, first, in new and improved mechanism for varying the speed of the grain-delivering mechanism, so as to deposit any desired quantity upon a given area of ground; second, in an improved device for throwing the feed mechanism out of gear by the act of raising the hoes; third, in an improved manner of constructing the feed-box, through which grain is passed from the hopper to the drill-tubes; fourth, in an improved grass-seed apparatus.

To enable others skilled in the art to which my invention appertains to fully understand and use the same, I will proceed to describe its construction and operation.

A A A represent various parts of the main frame of the machine, running upon two wheels, B B', the former of which is keyed to the axle b , while the wheel B' runs loosely on the axle, so as to adapt the machine to turn freely. The axle b carries a common cog-wheel, C, and a bevel cog-wheel, D, the uses of which will be hereinafter explained.

E represents the grain-hopper, and F a hopper for grass-seed. The bottom of the hopper F is formed of a gage-plate, G, supported by brackets G' and perforated with tapering apertures g , which may by the adjustment of the plate G be made to project beyond the edges of the brackets to any suitable distance, so as to expose such an area of apertures as may be adapted to the kind and quantity of seed to be sown.

H is a stirrer, to which a reciprocating motion is imparted through the medium of a connecting-rod, h, working upon an eccentric wrist, i, on the upper end of a vertical shaft, I, which receives a rotary motion from the bevel-gear wheel D upon the axle b , gearing with the bevel-pinion i' on the shaft I.

Through the perforated bottom e of the grain-hopper E the grain is received in feed or delivery boxes J, of peculiar construction, constituting secondary hoppers, one of which is employed for every hoe or drill tooth. The construction of these secondary or delivery hoppers will be better understood from Fig. 4, which represents a perspective view of one of the said hoppers on a larger scale.

j is a concave cast in one piece with cheeks $j' j'$, projecting inward from each side to afford end bearings for the feed-wheel K. An inclined plate, j^2 , covers the feed-wheel in such a manner as to prevent the descent of grain in the rear of the wheel. The wheels K are formed on their peripheries with teeth or cavities, as shown, and are all secured to a common shaft, k, which extends from side to side of the machine, and is rotated in the direction indicated by the arrow through the medium of a double intermediate gear-wheel, C', gearing with the wheel C upon the axle b , and with the wheel L upon the shaft k. In the illustration given in the drawings the smaller part, 1, of the wheel C' gears with the wheel L, and the larger part, 2, with the wheel C. The effect of this will manifestly be to rotate the feed-shaft k at a lower rate of speed; but by reversing the wheel C' the rate of rotation of the feed-shaft may be largely increased.

Fig. 5 shows the relative diameters of the two parts of the wheel C'. Fig. 6 shows a wheel, C², formed in two parts of more nearly equal diameter, but having a combined diameter equal to that of the two parts of the wheel C'. Fig. 7 shows a wheel in which the two

parts are still more nearly equal in diameter, and Fig. 8 one in which the two parts are of equal diameter. The sum of the radii of the two parts of each of the respective wheels being equal, it will be evident that either wheel, in whichever of its two positions it may be placed, will exactly occupy the space between the peripheries of the wheels C and L; but every change in the wheels C' C² C³ C⁴ changes center upon which they turn. The wheels are therefore fitted to turn upon a hollow shaft, M, which is held in any required position between two slotted brackets, N N', by means of a tapering horizontal bolt, O, passing through the said shaft, and provided at one end with a head, o, and at the other end with a clamp-nut, o'. The slots in the brackets N N' extend directly between the axle b and shaft k, so that the adjustment of the hollow shaft M up or down in the said slots will vary its relative distance from the axle b and shaft k as may be needful. To secure the shaft in any required position the bolt O is squared or tongued for a short distance near its head, so as to fit in notches n within the bracket N, and the inner end of the hollow shaft M is provided with tongue, m, which engage in notches n' on the face of the bracket N' when the bolt and shaft are drawn home by means of the nut o'. The notches in the brackets N N' correspond in number with the changes of which the wheels are susceptible. In the present illustration the four wheels (three of them reversible) are capable of seven changes, and accordingly there are seven notches in each of the brackets. To use the wheel C' the shaft is fixed in either the upper or lower notches, as the case may be, for the wheel C² in those next to the upper or lower notches, for the wheel C³ in those immediately above or below the center, and for the wheel C⁴ in the center notches.

P is a hinged cap or hood, covering the gear-wheels to prevent dirt or trash falling upon them to choke or injure them.

The wheel L is fitted to turn loosely on the shaft k, but imparts rotation thereto in one direction by means of a ratchet-rack, k', with which it is pressed in contact by a spring, k². By this means the backward motion of the wheel B is made to turn the wheel L freely upon the shaft k without imparting any motion thereto.

From the delivery-hoppers J the grain is discharged into spouts Q, which convey it to flexible tubes R, communicating with the hollow drill teeth or hoes S, in customary manner. The said hoes are each provided with two flanges, s, by which they are pivoted and

braced by iron and wooden pins to drag-bars T, hinged to the forward part of the frame. The hoes may be arranged either in a single rank across the machine, or (as in the present illustration,) in two ranks—one in advance of the other—the spouts Q being inclined alternately backward and forward to convey the grain to the tubes. The drill teeth or hoes are suspended by chains u from a hinged bar, U, which is provided with a lever, V, by means of which it may be turned up to raise all the hoes simultaneously, in which position the lever is held by a catch, v, upon the hopper when it is desired to remove the machine from place to place without depositing seed.

To prevent the operation of the seeding mechanism while the hoes are elevated, the bar U is provided with a projecting plate, u', which, when the said bar is turned up, acts upon the rear end of a lever, W, fulcrumed at w to the main frame, and engaging over a flange, l', on the wheel L, so as to draw the said wheel out of contact with its clutch, and thus permit the wheel to turn freely on the shaft.

Having thus described my invention, what I claim as new and of my invention, and desire to secure by Letters Patent, is—

1. The use of double reversible intermediate gear-wheels, substantially as shown and described, to communicate motion at any desired speed from the main axle to the seed-delivery apparatus.

2. The manner of attaching the movable shaft M at any suitable position between the axle b and shaft k to adapt it to the different sizes or positions of the intermediate wheels.

3. The combination of the lever W and flange or cam u' with the pivoted bar U and wheel L to disconnect the said wheel with the shaft k by the act of raising the hoes.

4. The concave j of the secondary or delivery hopper cast in one piece with cheeks j' j', all as herein shown and described.

5. The combination of the concave j, inclined plate j², cheeks j', and feed-wheel K, all constructed and arranged substantially as herein shown and described.

6. The movable bottom or gage plate G, perforated with tapering apertures g, in the described combination with the supporting-brackets G', so arranged that the said brackets may cover any desired part of the apertures to regulate the delivery of seed, as explained.

JOSEPH INGELS.
